CLAIM

The ornamental design for a band-mounted wireless remote control, as shown and described.

(22) Filed: **Jan. 8, 2013**

DESCRIPTION

(51) **LOC (10) Cl.** 14-03

FIG. 1 is a front view of the band-mounted wireless remote control;

(52) **U.S. Cl.** D13/168

FIG. 2 is a rear view of the band-mounted wireless remote control;

USPC D13/168

FIG. 3 is a top view of the band-mounted wireless remote control;

(58) **Field of Classification Search**

FIG. 4 is a bottom view of the band-mounted wireless remote control;

USPC D13/168; D14/155, 218; D10/49, 50;
341/176; 345/169; 340/4.3, 4.42,
340/12.22, 12.23, 12.24, 12.29, 12.3, 12.55,
340/13.2, 13.21, 13.24; 455/92, 95, 128,
455/151.1–151.4, 352, 353; 700/17, 65, 83

FIG. 5 is a left view of the band-mounted wireless remote control;

See application file for complete search history.

FIG. 6 is a right view of the band-mounted wireless remote control;

(56) **References Cited**

FIG. 7 is a perspective view of the band-mounted wireless remote control; and,

U.S. PATENT DOCUMENTS

FIG. 8 is a reverse perspective view of the band-mounted wireless remote control.
